United States Patent Office.

TORWALD WINTER, OF BOSTON, MASSACHUSETTS.

Letters Patent No. 77,697, dated May 5, 1863.

IMPROVED CHAIR AND LOUNGE.

The Schedule referred to in these Letters Patent and making part of the same.

TO ALL WHOM IT MAY CONCERN:

Be it known that I, TORWALD WINTER, of Boston, in the county of Suffolk, and State of Massachusetts, have invented an Improvement in Chairs and Lounges; and I do hereby declare that the following, taken in connection with the drawings which accompany and form part of this specification, is a description of my invention sufficient to enable those skilled in the art to practise it.

The invention relates particularly to the construction of chairs or chair-backs and seats, to be used in connection with lounges or sofa-couches, and consists primarily in combining a rotary seat and back with a lounge frame, in such manner that said seat and back may be brought into position to form a part of the bed-surface of the lounge and the head thereof, or may be swung around so as to form a chair at one end of the lounge.

The drawing represents a lounge embodying the invention.

A shows a side elevation.

B, a plan.

C, a section on the line *x x*.

a denotes the lounge-frame, standing on legs, *b*, and having an ordinary back, *c*. *d* denotes the rotary head of the lounge, having a round chair-seat, *e*, from the under surface of which a central spindle or axle, *f*, projects vertically through a bearing, *g*, in a bed-piece, *h*. This bed-piece has a circular flange or shoulder, *i*, into which the seat *e* fits, and the under surface of the seat is provided with a series of friction-rolls, *k*, which rest and roll upon the upper surface of the bed-piece *h*. The chair-seat, *e*, has a back, *l*, and arms *m m*, and when the chair is rotated to bring its open front into line with the lounge, the arm *n* comes into line with the lounge-back *c*, as seen at B, and to hold it in this position, to keep it from swinging further, a pin, *o*, projects from the bottom of the seat *e*, and brings up against a pin, *p*, projecting up from the bed-piece *h*.

The seat being in this position forms a very convenient head for the lounge, as will be readily understood from the drawings.

But if it be desirable to form a chair, or to bring the feet of the recumbent to the floor, the seat is rotated and readily brought to the position shown by red lines at A and B, or the chair-seat may be still further rotated so as to bring the open part of the chair to the extreme end of the lounge, the pins *o* and *p* again colliding and steadyng the chair in this position.

This construction is very useful to an invalid, as it permits him or her to bring the chair into direct connection with or so as to form a part of the couch, or to swing the seat around to form the chair, without any necessity for rising from the seat.

The manner of mounting the rotary seat with respect to the base upon which it rotates and is supported, is also applicable to a rotary chair not connected with a lounge, the support of the seat at its edges by the rollers preventing the seat from sagging, as it inclines to do when supported only at its centre, as in chairs having rotary seats as now made.

I claim the combination and arrangement of the rotary chair-seat and back and the lounge-frame, substantially as shown and described.

I also claim combining with a rotary chair-seat, rollers *k*, supporting the seat upon a bed-piece, *h*, and enabling the chair to be rotated upon said bed-piece, substantially as described.

TORWALD WINTER.
